ANKLE WEIGHT FOR EXERCISING PURPOSES

Doris M. McCrory and James G. McCrory, both of 1123 W. Clark, Berne, Ind.

Filed Aug. 5, 1965, Ser. No. 86,466

Term of patent 14 years

(Cl. D34—5)

FIG. 1 is a perspective view of an ankle weight for exercising purposes showing our new design;

FIG. 2 is a rear elevation thereof;

FIG. 3 is a perspective view thereof wherein the retaining strap is provided with a snap closure at one end; and

FIG. 4 is a rear elevation of the ankle weight for exercising purposes shown in FIG. 3.

The broken line shown indicating a foot in FIGS. 1 and 3 is for illustrative purposes only.

We claim:

The ornamental design for an ankle weight for exercising purposes, as shown and described.
